HIGH-SPEED CARRYING MEANS FOR CARD COUNTING MACHINES

Nelson S. Welk, Athens, Ohio, assignor to The McBee Company, Athens, Ohio, a corporation of Ohio

Original application July 26, 1939, Serial No. 286,570. Divided and this application April 2, 1940, Serial No. 327,417

10 Claims. (Cl. 271—51)

My invention relates more particularly to that class of machines which are designed to count record cards, checks, coupons and the like such as is described in my copending application, Serial 5 No. 286,570, of which this application is a division.

Commercial machines of this type are generally too slow to be desirable and when speeded up they become inaccurate. This is due to the 10 type of devices employed to carry or convey the cards to be counted to and from the counting mechanism.

In my invention I provide a number of pairs of rollers which I term wringer rolls, for the reason 15 they are in pairs, only one of which is driven and they squeeze the cards between them. These rolls are driven at high speed.

The principal object of my invention is to provide high speed means to carry cards from the 20 feeding device through the counting mechanism and deliver them in sequential arrangement.

A further object is to provide two sets of high speed conveying means to rotate at different speeds.

25 A further object is to provide for slight slippage of the cards between the first set of high speed conveying means.

My means of accomplishing the foregoing objects may be more fully comprehended by having 30 reference to the accompanying drawings which are hereunto annexed and are a part of this specification in which:

Fig. 1 is a side elevation view of my high speed card carrying means with parts of the machine 35 being broken away and shown in section for clarity;

Fig. 2 is a top or plan view of Fig. 1;

Fig. 3 is a cross sectional view showing the first set of wringer rolls and their adjusting 40 means taken on the line 3—3 of Fig. 1 and looking in the direction of the arrows;

Fig. 4 is a cross sectional view showing the second set of wringer rolls and counter taken on the line 4—4 of Fig. 1 and looking in the direction 45 of the arrows;

Figs. 5 and 6 are elevational and top plan detail views respectively, of the upper wringer roll of the second set of wringer rolls, the plan view being partly in section; and

50 Fig. 7 is a diagrammatic view showing the operation of feeding the cards, etc. Similar reference numerals refer to similar parts throughout the entire specification.

In machines of this type, a feeder is provided 55 adapted to receive a stack of cards C which rest

upon feed rollers and are held in position by means of locating plates.

Adjacent to and in the rear of the main feeding roll 1, I locate a roller 2, which I have found in practice should be made of steel. Above this 5 roller 2 I mount a shaft 3' which carries a plurality of spaced rolls 3 which are preferably made of hard rubber or a similar substance. The roll 2 is mounted upon the shaft 2'. Means to insure a close contact between the surface 10 of these wringer rolls 2 and 3 is provided by means of coil compression springs 5 and 5' which exert a pressure upon bearings 6 and 6' in which revolve the shafts 2' and 3' which carry the rolls 2 and 3.

These bearings, which are preferably made from bronze or other suitable bearing metal, are provided with slots to slide on a guide cut in the side plates of the machine.

Metal plungers 7 and 7' are inserted in the 20 coil compression springs 5 and 5'. These plungers provide an enlarged surface at the top for contact with the adjusting screws 8 and 8' which are threaded into blocks 9 and 9', which span the gap cut in the side plates to permit the insertion 25 of the bearings 6 and 6'. These blocks may be secured in place in any suitable or convenient manner. As shown, they are held by means of screws 10 and 10'.

The shaft 2' which carries the lower wringer 30 roll 2 has a spur pinion 11 mounted on its extreme right hand end. This pinion is rotated by an idler gear 12 which revolves on a stud 13 fastened to the right side panel by means of a nut in the conventional manner which is so well understood so as not to require specific description. The idler gear 12 in turn is driven by a gear 35 connected to the main drive (not shown). In front of the wringer rolls 2 and 3 I mount a cross bar 14 to which is secured a counting device 40 15 of standard construction. This counting device is a commercial product which is familiar to those skilled in the art and for that reason I shall not describe its construction.

I remove the metal finger, which is usually 45 provided on such a counting device, and which is generally attached to the lower shaft of the counter. In the place of the metal finger I mount a three-legged paddle wheel 16 the legs of which terminate in feet which are shaped 50 as shown in the drawings. The feet are adapted to contact the edge of the card as it passes through the machine. At the rear of the counting device 15 I mount a second set of pairs of wringer rolls 17 and 18. I have found it desir- 55

able to construct the lower one 11 of this set of rolls of a medium soft rubber as that has been found most satisfactory in practice. It may be provided with a steel core or shaft 17', the ends 5 of which are fitted into bearings in the side panels.

On the right hand end of the core or shaft 17' I mount a spur pinion 19, the teeth of which mesh with the gear 12 and is rotated thereby. 10 The upper wringer rolls 18 of this set are clearly seen in the detail views, Figs. 5 and 6, as shown there are four of them, preferably made of steel. These rolls 18 are preferably mounted on roller or ball bearings, which are carried by studs 20. 15 The anti-friction bearings are necessary due to the high speed at which they rotate. In Fig. 6, I have shown one of the wringer rolls 18 in section to show the stud 20 upon which it revolves. As the construction of each of these wringer rolls 20 is identical, I shall only describe one of them.

The stud 20 on which the upper wringer rolls 18 of this set revolve, is threaded or suitably pressed into a swinging arm 21. Means for regulating the friction between these rolls 18 and 25 the lower roll 17 is provided by flat springs 22, which are preferably secured to the under side of a collar 23, by means of screws or any other suitable manner. The collar 23 is preferably secured to a bushing 24 by a press fit. After the 30 desired pressure upon roller 18 exerted by the spring 22 has been found to be correct, the bushing 24 is locked to the cross bar 14 by set screw 24'. The swinging arm 21 is free to rotate on bushing 24. The cross bar 14 is preferably supported at its ends in the side panels. It will be 35 apparent by rotating the bushing 24 upon the cross bar 14, the tension of the flat springs 22 can be regulated.

The operation

40 A stack of cards of approximately 500 in number are placed on a flat surface and "jogged" until their edges are even. The cards are "jogged" preferably when held at an angle to their face, 45 thus providing a bevelled arrangement for loading onto the inclined surface of the card support. Locating plates are then adjusted on a cross rod to suit the width of the cards which are to be counted. When this adjustment is made, the 50 locating plates are retained in their position by means of set screws.

The machine is now ready to begin the counting operation. The motor is started and through the medium of the belt, pulleys and trains of 55 gears, the various rotating parts are revolved. The frictional contact against the surface of the feed roll which is usually made of rubber, on the bottom card of the stack of cards, will cause the bottom card to be fed rearwardly.

60 As the cards are fed from the bottom at a rate which is as high as 50,000 an hour for small cards, the separation of one card from another longitudinally is only slightly more than the thickness of the cards, due to the fact that the 65 one next to the bottom card is given motion just as soon as it is exposed by the movement of the bottom card. As the bottom card is fed rearwardly by the feed roller, its edge is caught between the first set of wringer rolls 2 and 3 which 70 carries it rearwardly rapidly causing its edge to abut one of the legs of the paddle wheel 16 of the counting device.

The natural tendency of the card as it passes through the wringer rolls 2 and 3 is to assume 75 a horizontal position. I prevent this by the down-

ward inclination of a hold-down plate. This inclination also prevents the cards from riding upwards.

The card now is caught between the second set of wringer rolls 17 and 18 which are preferably located about $\frac{1}{4}$ of an inch below the first set, these rolls again cause the card to assume a horizontal position as soon as it is released from the first set of wringer rolls.

Each pair of the wringer rolls 17 and 18 are 10 revolved at a higher rate of speed than the wringer rolls 2 and 3. This speed should be sufficient to advance the cards approximately $\frac{1}{4}$ of an inch, this being permitted by the slippage between the upper wringer roll 3 and the lower 15 one 2, thus insuring clearance between the counted card and the card following.

From this point the cards are deposited upon a suitable conveyor as clearly described in the said copending application, Serial No. 286,570 20 and shown herein in the diagrammatic view, Fig. 7.

It will be clear from the foregoing description that this construction will overcome the objections before referred to, and that regardless of 25 the speed at which the machine is operated, there will be no inaccurate counting. In practice, I have found the machine will correctly count up to 50,000 per hour correctly and deposit 30 the cards in numerical sequence on the conveyor.

Although I have described with some degree of particularity, a preferred construction, I do not desire to be understood as limiting myself thereby, as this description is furnished solely to illustrate a preferred embodiment of my invention, 35 as many mechanical changes will suggest themselves in manufacturing my device, and I do not wish to be limited, except as such limitations may appear in the hereinafter contained claims.

Having described my invention, what I regard 40 as new and desire to secure by Letters Patent is:

1. In a card counting machine having an adjustable card support, an adjustable caliper, a main feed roll, the plane of feed of said roll being horizontal, two sets of rolls, a counting mechanism intermediate said sets of rolls and means to rotate the lower rolls; the point of contact of the first set of rolls being located below the plane of the upper surface of the main feed roll, the plane of feed of the first set of rolls being parallel to and below the plane of feed of the main feed roll, whereby a card entering between them is caused to snap downwardly thus clearing the next succeeding card being fed.

2. In a card counting machine having an adjustable card support, an adjustable caliper, a main feed roll, the plane of feed of said roll being horizontal, two sets of rolls, a counting mechanism intermediate said sets of rolls and means to rotate the lower rolls; the point of contact of the first set of rolls being located below the plane of the upper surface of the main feed roll, the plane of feed of the first set of rolls being parallel to and below the plane of feed of the main feed roll, the point of contact of the rear set of rolls being located on a lower plane than the first set, the planes of the axis of the pairs of rolls being parallel to feed in planes parallel to the plane of feed of the main feed roll, whereby a card entering between them is caused to snap downwardly thus clearing the next succeeding card being fed.

3. In a card counting machine having an adjustable card support, an adjustable caliper, a main feed roll, the plane of feed of said roll being horizontal, two sets of rolls, a counting mechanism intermediate said sets of rolls and means to rotate the lower rolls; the point of

contact of the first set of rolls being located below the plane of the upper surface of the main feed roll, the point of contact of the rear set of rolls being located on a lower plane than the first set, the planes of the axis of the pairs of rolls being parallel to feed in planes parallel to the plane of feed of the main feed roll, whereby a card entering between them is caused to snap downwardly thus clearing the next succeeding card being fed, and means to rotate the rear set of rolls at a higher rate of speed than the front set.

4. In a card counting machine having an adjustable card support, an adjustable caliper, a main feed roll, the plane of feed of said roll being horizontal, two sets of rolls, a counting mechanism intermediate said sets of rolls and means to rotate the lower rolls; the point of contact of the first set of rolls being located below the plane of the upper surface of the main feed roll, the planes of the axis of the pairs of rolls being parallel to feed in planes parallel to the plane of feed of the main feed roll, whereby a card entering between them is caused to snap downwardly thus clearing the next succeeding card being fed, means to continuously rotate one of the lower rolls at a higher rate of speed than the other roll.

5. In a card counting machine having an adjustable card support, an adjustable caliper, a main feed roll, a counting mechanism, a shaft which extends across said machine in front of said counting mechanism; a roll having a continuous surface carried thereby, a second shaft above the first named shaft, spaced rolls thereon the surfaces of which contact said roll, a shaft which extends across said machine in the rear of said counting mechanism, a roll having a continuous surface carried thereby, individual studs above said last named shaft, individual rolls carried thereby the surfaces of which contact said last named roll, means to rotate the shaft on which the lower rolls are mounted, and means to rotate one of said shafts at a higher rate of speed than the other.

6. In a card counting machine having an adjustable card support, an adjustable caliper, a main feed roll, two sets of rolls, a counting mechanism intermediate said sets of rolls and means to rotate the lower rolls; the point of contact of the first set of rolls being located below the plane of the upper surface of the main feed roll, the point of contact of the rear set of rolls being located on a lower plane than the first set, whereby a card entering between them is caused to snap downwardly thus clearing the next succeeding card being fed, the front set of rolls comprising a shaft which extends across said machine in front of said counting mechanism, a roll having a continuous surface carried thereby, a second shaft above the first named shaft, spaced rolls thereon the surfaces of which contact said roll, a shaft which extends across said machine in the rear of said counting mechanism, a roll having a continuous surface carried thereby, individual studs above said last named shaft, and individual rolls carried thereby the surfaces of which contact said last named roll.

7. In a card counting machine having an adjustable card support, an adjustable caliper, a main feed roll, two sets of rolls, a counting mechanism intermediate said sets of rolls and means to rotate the lower rolls; the point of contact of the first set of rolls being located below the plane of the upper surface of the main feed roll, the point of contact of the rear set of rolls being

located on a lower plane than the first set, whereby a card entering between them is caused to snap downwardly thus clearing the next succeeding card being fed, the front set of rolls comprising a shaft which extends across said machine in front of said counting mechanism, a roll having a continuous surface carried thereby, a second shaft above the first named shaft, spaced rolls thereon the surfaces of which contact said roll, a shaft which extends across said machine in the rear of said counting mechanism, a roll having a continuous surface carried thereby, individual studs above said last named shaft, individual rolls carried thereby the surfaces of which contact said last named roll, and anti-friction bearings on which said individual rolls rotate.

8. In a card counting machine having an adjustable card support, an adjustable caliper, a main feed roll, two sets of rolls, a counting mechanism intermediate said sets of rolls and means to rotate the lower rolls; the point of contact of the first set of rolls being located below the plane of the upper surface of the main feed roll, the point of contact of the rear set of rolls being located on a lower plane than the first set, whereby a card entering between them is caused to snap downwardly thus clearing the next succeeding card being fed, the front set of rolls comprising a shaft which extends across said machine in front of said counting mechanism, a roll having a continuous surface carried thereby, a second shaft above the first named shaft, spaced rolls thereon the surfaces of which contact said roll, a shaft which extends across said machine in the rear of said counting mechanism, a roll having a continuous surface carried thereby, individual studs above said last named shaft, individual rolls carried thereby the surfaces of which contact said last named roll, and anti-friction bearings on which said individual rolls rotate.

9. In a card counting machine having an adjustable card support, an adjustable caliper, a main feed roll, a counting mechanism, a shaft which extends across said machine in front of said counting mechanism; a roll having a continuous surface carried thereby; a second shaft above the first named shaft, spaced rolls thereon the surfaces of which contact said roll, a shaft which extends across said machine in the rear of said counting mechanism, a roll having a continuous surface carried thereby, individual studs above said last named shaft, individual rolls carried thereby the surfaces of which contact said last named roll, means to rotate the shafts on which the lower rolls are mounted, means to rotate one of said shafts at a higher rate of speed than the other, a cross bar, arms in which said studs are mounted, means to swingingly mount said arms on said cross bar, bushings rotatable on said cross bar, springs the outer ends of which bear on said studs, means to permit the tension of said springs to be varied, and means to lock said last named means.

10. In a card counting machine having an adjustable card support, an adjustable caliper, a main feed roll, a counting mechanism, a shaft which extends across said machine in front of said counting mechanism; a roll having a continuous surface carried thereby, a second shaft above the first named shaft, spaced rolls thereon the surfaces of which contact said roll, a shaft

which extends across said machine in the rear of said counting mechanism, a roll having a continuous surface carried thereby, individual studs above said last named shaft, individual rolls carried thereby the surfaces of which contact said last named roll, means to rotate the shafts on which the lower rolls are mounted, means to rotate one of said shafts at a higher rate of speed than the other, a cross bar, arms in which said 10 studs are mounted, means to swingingly mount said arms on said cross bar, bushings rotatable on

said cross bar, springs the outer ends of which bear on said studs, means to permit the tension of said springs to be varied and means to lock said last named means, the point of contact of the front set of rolls being located below the plane 5 of the upper surface of the main feed roll, the point of contact of the rear set of rolls being located on a lower plane than the first set, whereby a card entering between them is caused to snap downwardly clearing the card following. 10

NELSON S. WELK.
